INTERLOCKING BRICKS

Charles J. Lacy, Olivette, Mo.

Application August 26, 1950, Serial No. 181,656

3 Claims. (Cl. 72—38)

1

My invention relates to key interlocked bricks for use in building walls and similar structures.

An object of the present invention is to provide bricks that will permit the rapid, comparatively inexpensive laying of same into a wall, or similar structure wherein adjacent bricks in each course will be key interlocked, and, wherein adjacent bricks in an adjacent course next above will be key interlocked with the bricks next below.

A further object of the invention is to provide bricks, rectangular in shape, having like intersecting longitudinal and transverse grooves on the top and bottom faces thereof, vertical end face grooves, and a vertical side face groove which when the bricks are laid into a wall, or similar structure adjacent bricks laid end to end, end to side, and side by side may be interlocked by a T-shaped key, the leg of the key interlocking adjacent bricks in each course, and the cross-head of the key interlocking adjacent bricks in the adjacent course next above in break joint relation.

Other objects and advantages of the invention will be apparent during the course of the following description.

In the drawings forming a part of this application:

Fig. 1 is a perspective view of the corner brick of the brickwork of Figs. 6, 7 and 8.

Fig. 2 is a perspective view of the intermediate brick adapted to be positioned in a structure between corner bricks.

Fig. 3 is a vertical sectional view of the corner brick taken on line 3—3 of Fig. 1.

Fig. 4 is a sectional view of the intermediate brick taken on line 4—4 of Fig. 2.

Fig. 5 is a perspective view of the T-shaped key for interlocking adjacent brick, both horizontally and vertically.

Fig. 6 is a plan view of one course of brickwork showing the vertical key leg receiving openings between adjacent bricks at the corner of a wall structure.

Fig. 7 is a perspective view of the brickwork shown in Fig. 6, illustrating the keys for interlocking the bricks.

Fig. 8 is a vertical sectional view of a plurality of courses of the brickwork showing adjacent bricks in interlocked relation.

Fig. 9 is a perspective view of several courses of the corner brickwork of the present invention.

Fig. 10 illustrates adjacent bricks interlocked in side by side relation.

In the drawings, wherein for the purpose of illustration, is shown a preferred embodiment of my invention, the numeral 11 designates, gener-

ally, a corner brick, the numeral 12 designates, generally, a brick to be laid between corner bricks, and the reference numeral 13 designates, generally, a T-shaped brick aligning key for interconnecting adjacent bricks in a course, and adjacent bricks in adjacent courses.

The intermediate brick 12, as shown, includes a rectangular body having horizontal straight walled intersecting longitudinal and transverse key-way grooves designated 14 and 15, respectively, on opposite faces of the brick, that is, the upper and lower faces thereof. The body also includes corresponding straight walled vertical key-way grooves 16 on the end faces of the brick which communicate with the ends of the longitudinal grooves 14. The body also includes a corresponding straight walled vertical key-way groove 17 on one of the side faces of the brick which communicates with one end of the transverse grooves 15. One end of each of the transverse grooves is closed, as at 18, to provide a blind end for each transverse groove.

The corner brick 11, as shown, is identical in size and shape as the brick 12, except that one end of each of the longitudinal grooves is closed, as at 19, to provide a blind end for each longitudinal groove. Thus, the corner brick 11 is provided with the intersecting longitudinal and transverse grooves designated 14 and 15, respectively, on opposite faces of the brick, the vertical side face groove 17, but is only provided with one vertical end face groove 16.

The key 13, as shown in Fig. 5, is T-shaped in formation providing thereby a leg 20 and a cross-head 21. The key may be made from any suitable material, preferably metal, although not necessarily so. The key 13 is of such thickness as to correspond to and engage mating grooves on the several faces of adjacent bricks, dependent upon whether the bricks are laid end to end, end to side such as the adjacent corner bricks, or side by side, if desired to do so. They key 13 projects beyond the edges of the grooves of one brick and engages corresponding mating grooves on an adjacent brick, thereby preventing the shifting of the bricks relative to each other.

As shown in Fig. 6, when adjacent intermediate bricks 12 are laid end to end, in a course, a vertical opening 22 is formed at the joint between adjacent bricks by the mating vertical end face grooves 16, and when adjacent bricks are laid end to side, in a course, a vertical opening 22 is formed at the joint between the adjacent bricks by the mating of an end face groove 16 with a side face groove 17 into which opening 22 is fitted the leg 55 20 of the key 13.

The lower half of the two projections of the cross-head 21 of the key engages the longitudinal grooves 14 when adjacent bricks are laid end to end, and engages a longitudinal groove 14 and a transverse groove 15 when adjacent bricks are laid end to side. The upper half of the head 21 engages in corresponding mating grooves on the bottom faces of the bricks in the course next above, as shown in Fig. 8.

This arrangement of interlocking adjacent bricks and interlocking bricks in adjacent courses, is simple, quick, highly efficient and results in a straight wall from corner to corner, with no danger of bricks shifting one relative to the other. A thin coating of mortar may be used between adjacent bricks, as indicated in Figs. 6 and 8. The groove spaces not interrupted by the heads of the key 13 provide a multiplicity of dead air pockets in a wall structure.

In Fig. 7, there is illustrated, in perspective, the bricks shown in Fig. 6, but showing adjacent bricks interlocked by means of keys 13.

Fig. 9 clearly shows, in perspective, three courses of a corner brickwork in a wall structure showing adjacent bricks as interlocked by the keys 13.

From the drawings, and the foregoing description, it will be clearly apparent adjacent bricks in each course of brickwork may be interlocked end to end, side to end, and side by side, as well as face to face in adjacent courses.

The many advantages of the herein described invention will readily suggest themselves to those skilled in the art to which the invention relates.

The invention may be carried out in other specific ways than those set forth without departing from the spirit and essential characteristics of the invention, and the present embodiments are illustrative and not restrictive, and all changes coming within the meaning and equivalency range of the appended claims are intended to be embraced therein.

What I claim is:

1. A two-thickness interlocked wall of building bricks that comprises a plurality of elongated, rectangular bricks in superposed courses, with two parallel, longitudinal rows of bricks forming each course, each brick having longitudinally extending grooves in the top and bottom thereof, said grooves having parallel faces similarly spaced, and being located at the transverse center of said brick, end grooves of the same width as the longitudinally extending grooves in each

end of said brick in alignment with said longitudinally-extending grooves and communicating therewith, transversely-extending grooves in the top and bottom of said brick, said transverse grooves having parallel faces spaced apart a distance similar to the width of the longitudinal grooves, and being spaced from one end of each brick a distance equal to one-half the width of said brick and being joined by a side groove in one side face of said brick, of a width similar to the width of the transverse groove and in alignment therewith, and aligning elements for aligning said bricks both vertically and horizontally, one aligning element spanning a pair of superimposed rows of two adjacent courses, a portion of said element being seated in the longitudinal grooves of the bricks of said two rows and extending into the end grooves of adjacent bricks of one of said two rows, and a second aligning element extending transversely of the wall and having a portion seated in said transverse grooves of the bricks of said pair of rows and in the transverse grooves of the adjacent pair of rows of said two adjacent courses, said second aligning element having another portion extending into the side grooves of adjacent bricks of the parallel rows in one course of said two adjacent courses.

2. A wall as claimed in claim 1, in which the transverse grooves in the brick extend inwardly from one side face thereof, but terminate short of the opposite side face thereof.

3. A wall as claimed in claim 1, in which the transverse grooves in the brick extend inwardly from one side face thereof, but terminate short of the opposite side face thereof, and in which certain of said bricks have the longitudinal grooves extending inwardly from one end of the brick, but terminating short of the opposite end thereof.

CHARLES J. LACY.
